ELECTRICAL NETWORK FOR DETECTING HEAT DUE TO VARIOUS CAUSES

Clifford John Klein, Riverdale, N. J., assignor to Specialties Development Corporation, Belleville, N. J., a corporation of New Jersey

Application October 27, 1955, Serial No. 543,083

12 Claims. (Cl. 340—233)

The present invention relates to electrical networks which are automatically responsive to temperature conditions, and, more particularly, to such networks which can discriminate between a sudden fire, an overheat condition and a slowly burning fire.

The present invention is primarily concerned with improving heat and flame detecting systems. In such systems, an element is utilized which comprises two conductors spaced apart by a material having an infinitely high resistance at a normal temperature to render it substantially non-conductive to electricity and having the characteristic of being rendered conductive at an abnormal high temperature, and suitable means indicate or operate various devices when the abnormal temperature condition has been detected due to a slowly burning or sudden fire.

Accordingly, the primary object of the present invention is to provide an improved network of such type which is also capable of detecting the presence of an abnormal overheat condition existing independently of a fire.

Another object is to provide such a network which discriminates between a fire and an overheat condition.

Another object is to provide such a network which discriminates between a fixed temperature fire and an overheat condition.

Another object is to provide such a network which is constructed of a minimum number of relatively inexpensive, lightweight components adapted to be arranged in a compact manner.

Another object is to provide such a network which has a long useful life and requires a minimum of maintenance or repair.

A further object is to provide such a network which has utility in a great many fields of application.

Other and further objects of the invention will be obvious upon an understanding of the illustrative embodiment about to be described, or will be indicated in the appended claims, and various advantages not referred to herein will occur to one skilled in the art upon employment of the invention in practice.

In accordance with the present invention, it has been found that the foregoing objects can be accomplished by providing a voltage dividing bridge type network which essentially comprises a source of unidirectional electrical current, first and second resistance elements connected in series across the source, parallel third and fourth resistance elements and another resistance element connected in series across the source, the resistance elements having resistance values to provide a pair of voltage dividing bridges normally unbalanced in one direction and the first resistance element being constructed and arranged so that the resistance thereof changes in response to a predetermined condition to another value whereby the bridge is unbalanced in the opposite direction, and an electromagnetically operable device, such as a polarity indicator or polarity sensing device, connected in voltage dividing relationship across the third element and the

2

junction of the first and second resistance elements, and a second electromagnetically operable device connected in voltage dividing relationship across the fourth resistance element and the junction of the first and second elements.

5 In order to discriminate between a sudden fire and a slowly burning fire, a time constant network is connected in series with the first mentioned sensing device.

A preferred embodiment of the invention has been chosen for purposes of illustration and description, and 10 is shown in the accompanying drawings, forming a part of the specification, wherein:

Figs. 1 to 4 are circuit diagrams illustrating the essential components arranged in a network in accordance with the invention, under normal and detecting conditions.

15 Fig. 5 is a graph illustrating the ambient temperature conditions which may occur during the various stages of an airplane while in flight and the temperature resulting from fire and overheat conditions.

Referring to Fig. 1 of the drawings, a network is shown

20 which essentially comprises a source of unidirectional electrical current represented by conductors 10 and 11, a condition sensing resistor shown as a variable resistor 12 (first resistor), a fixed resistor 13 (second resistor), a pair of resistors 14 and 15 (third and fourth resistors), 25 a fixed resistor 16 (another or fifth resistor), a pair of polarity indicators or polarity sensing devices 17 and 18 each having a winding 19, upper and lower contacts 20 or 20a and 21 or 21a and a switch element 22 or 22a, respectively, and a pair of relays 23 and 24 each having 30 a winding 25, switch elements and contacts, as described hereinafter.

The source of current may be direct current from a battery or generator, or rectified alternating current. The conductor 10 is illustrated as being connected to the positive side of the source, and the conductor 11 is illustrated as being connected to the negative side of the source.

35 The condition sensing resistor 12 may be any element subject to changes in its resistance in response to the particular condition to be detected. For example, such an element may be sensitive to heat, light, humidity or mechanical force. In the illustrative embodiment of the invention described herein, such an element is utilized to detect heat or flame on aircraft, or other craft or vehicles, and comprises two conductors of electricity spaced 40 apart by a thermistor-like material having an extremely or infinitely high resistance at a normal temperature to render it substantially non-conductive to electricity and having the characteristic of being rendered conductive at an abnormal temperature caused by the heat of flame or fire. Such elements are well known in the art.

45 The resistors 13 and 16 are balancing resistors of the type which do not vary appreciably in resistance with ambient temperature changes and consequently remain in fixed ratio when subjected to temperatures ranging from 50 —65° F. to 160° F.

55 The resistors 14 and 15 are shown herein as voltage dividers and are adapted to provide a wide range in which the network may be accurately adjusted. These resistors also are practically immune to ambient temperature changes.

60 The successful operation of such a network depends greatly on the use of the ultra-sensitive polarity indicators 17 and 18 which are adapted to detect the change of polarity of the bridge error when the resistance of the sensing resistor 12 reaches a predetermined value. The switch element of each of these indicators is pivotally mounted for free, torqueless movement thereof and has no appreciable mass. Each switch element is under the control of its winding 19, as indicated by the broken lines, 65 whereby when current flows through the winding in one direction, the switch element engages the lower contact, and, when current flows through the winding in the op-

posite direction, the switch element engages the upper contact. The polarity indicator has no deflection gradient to speak of and thereby does not have any steady state intermediate position between the upper end and lower contacts.

The resistors 12 and 13 (first and second resistors) are connected in series across the conductors 10 and 11 (source of current), and the resistors 14 and 15 (third and fourth resistors) are connected in parallel, and in series with the resistor 16 (another or fifth resistor) across the conductors 10 and 11. One end or terminal of the winding of the polarity indicator 17 is connected to the effective junction of the resistors 14 and 16, that is, in voltage dividing relation with respect to the resistor 14, and the other end or terminal of this winding is connected in effect to the junction of the resistors 12 and 13.

The contact 20 of the indicator 18 is connected to the conductor 10 (one side of source) through a limiting resistor 26, and the contact 21 is connected to the conductor 11 (other side of source) by a conductor 27. One end of the winding of the relay 23 is connected to the switch element 22, and the other end of this winding is connected to the conductor 11. A diode 28 is connected across the winding between the conductor 11 and the switch element 22 to quickly short-circuit the relay 23 and cause it to drop out when the element engages its contact 21.

The relay 23 includes a switch element 30 which is movable between contacts 31 and 32, and a second switch element 33 adapted to engage a contact 34 connected to the conductor 10 through a limiting resistor 35 to lock in the relay upon operation thereof under control of the switch element 22 (Figs. 2 and 4). The switch element 30 is connected to the conductor 10, and the contact 32 is connected to one terminal of an alarm device, such as a lamp 36, which has its other terminal connected to the conductor 11, whereby upon operation of the relay the switch elements engage the contact 32 to energize the lamp.

The winding of polarity indicator 17 is protected against high voltage surges by a pair of varistors 37 and 38 arranged in opposite directions and connected in parallel across the winding. These elements decrease in forward resistance with an increase in voltage, whereby high voltage current flows through these elements to short-circuit the indicator winding and eliminate the effect of such surges thereon.

In the operation of the portion of the bridge network which involves the indicator 17, assuming that it is used as a heat or flame detector, the resistance of the resistor 14 is adjusted so that the network is in balance just before the resistor 12 is subjected to a fixed predetermined temperature condition it is designed to detect. The network then is out of balance at normal temperatures, and current tends to flow through the winding of the indicator 17 and the other components as illustrated by the arrows in Fig. 1, whereby the switch element 22 is held against the contact 21.

When the resistor 12 is subjected to a predetermined temperature caused by a fixed temperature fire for a sufficient duration, its resistance is lowered whereupon it becomes sufficiently conductive to pass current so that the bridge becomes unbalanced in the opposite direction with current flowing through the winding and the other components as illustrated by the arrows in Fig. 2, whereby the switch element 22 is moved into and held in engagement with the contact 20. This causes the relay 23 to be energized and close its alarm circuit.

After the condition which heated the resistor 12 no longer exists and this resistor cools and increases in resistance, the network is again unbalanced into its original direction (Fig. 1) causing the relay 23 to drop out.

Since it is desirable to discriminate between a fixed temperature fire and a sudden fire, the network so far described further includes a time constant or rate of change of condition network which is connected in series with the wind-

ing of polarity indicator 17 across the junction of resistors 12 and 13 and the junction of resistors 14 and 16. This network comprises a condenser 39, a resistor 40 and a diode 41 connected in parallel.

Depending on the rapidity of the change of condition (rate of change), the condenser causes this change or A.C. component to be impressed across the winding of the indicator 17 in the direction depending on the polarity of this changing potential.

10 The diode 41 is for the purpose of providing a short circuit for the polarity of the voltage indicated across it, and therefore will not cause a fixed temperature response point to be affected by the resistor-capacitor arrangement in parallel therewith, such polarity occurring when the bridge is unbalanced to indicate heat or fire.

The resistor 40 is utilized to provide a path for steady state reset current through the winding 19 (Fig. 1) to drop out the relay 23 and to hold the switch element 22 against its contact 21.

20 The time constant network is arranged to sense rate of change on an order which would take place in the event the detecting resistor 12 is subjected to the heat of a sudden flame, but not to sense more gradual ambient temperature changes which may occur under normal conditions of flight. To accomplish this a condenser 39 having a capacitance of 60 mf. and a resistor 40 having a resistance of 47 kilo-ohms are utilized.

25 The network involving the indicator 17 is further arranged so that the time constant network cannot sense rate of change at temperatures below a predetermined level below the fixed temperature response level. For example, the bridge resistors have resistances whereby rate of change can be detected above about 530° F. and a fixed temperature fire condition is detected at 700° F. This may be accomplished by utilizing resistors 13, 14, 16 and 12 having resistances of 8.2, 10 and 5 kilo-ohms, and more than 200 megohms, respectively, at about 70° F., the resistors 14 and 16 being adjusted in voltage dividing relationship to provide for polarity indicator response at the specified temperature as hereinafter described.

30 The resistance of the resistor 12 drops sharply above 500° F. and has a relatively low resistance value at the temperature the polarity indicator 17 responds, which resistance is so related to the resistance of the resistor 14 to place the bridge in balance as the responsive temperature is approached. Thus, when the resistor 12 cools slightly it increases rapidly in resistance ratio-wise to rapidly unbalance the bridge to the off direction whereby rapid resetting is effected. To accomplish this, the resistance of the resistor 12 decreases from about 37 kilo-ohms at 500° F. to 1150 ohms at 700° F. and vice versa.

35 In operation with the foregoing arrangement (Fig. 2), a high rate of change can be detected almost instantaneously above 530° F. to cause the polarity indicator 17 to move the switch element 22 into engagement with the contact 20 to effect actuation of the alarm 36, and a heat condition, which is caused by a very slow increase in temperature, also can be detected almost instantly after the detecting resistor 12 has been heated to 700° F.

40 When a flame detected by rate of temperature rise is rapidly extinguished and the detecting resistor is still at a temperature below 700° F., the bridge remains unbalanced to the condition indicated in Fig. 1. The alarm signal then disappears indicating that the fire is out, unless other conditions exist as explained hereinafter.

45 In certain fields of application, the detecting resistor may be subjected to a sudden flash of heat which endures for perhaps no longer than one second and in itself is not a dangerous condition to be detected. Thus, in order to prevent false alarms from being caused by such a condition, a filter-condenser 42 is connected across the winding of the polarity indicator 17 which functions to delay the operation of the indicator for about 2 or 3 seconds and thereby discriminate a fire from a heat flash.

50 As already indicated, the resistor 15 is connected in

parallel with the resistor 14 and in series with the resistor 16. Thus, by connecting one end or terminal of the winding of the polarity indicator 18 to the effective junction of the resistors 15 and 16, that is, in voltage dividing relation with the resistor 15, and the other end or terminal of this winding to the junction of the resistors 12 and 13, a double bridge network is provided in a simple and convenient manner.

The contact 20a of the indicator 18 is connected to the conductor 19 through a limiting resistor 26a, and the contact 21a is connected to the conductor 11 by a conductor 27a. One end of the winding of the relay 24 is connected to the switch element 22a of the indicator 18, and the other end of this winding is connected to the conductor 11. A diode 23a is connected across this winding for effecting quick return of the relay 24.

The relay 24 includes a switch element 45 connected to the contact 31 of the relay 23 and adapted to engage a contact 46 connected to one terminal of an alarm device, such as a lamp 47, which has its other terminal connected to the conductor 11 and a second switch element 33a connected to the switch element 22a and adapted to engage a contact 34a connected to the conductor 10 through a limiting resistor 35a to lock in the relay upon operation thereof.

At about 70° F., the resistors 13, 16 and 12 as previously mentioned, have resistances of 8.2 and 5.0 kilo-ohms and more than 200 megohms, respectively, and the resistor 15 has a resistance of 10.0 kilo-ohms, the resistors 15 and 16 being adjusted in voltage dividing relationship to provide for polarity indicator response at the specified temperature as hereinafter described. Since the resistance of the resistor 12 drops sharply above 500° F., the resistance values in this network enable the indicator 18 to detect a change in polarity in its network at about 600° F., and thereby respond and indicate the existence of an overheat condition below the temperature at which a fixed temperature fire condition is detected, as will be made apparent hereinafter. As mentioned before, when the temperature of the resistor 12 decreases, the resistance of this resistor increases rapidly to rapidly unbalance the bridge network to the off direction, whereby resetting is effected. For example, the resistance of the resistor 12 increases from about 6.8 kilo-ohms at 600° F. to about 37 kilo-ohms at 500° F.

In Fig. 5, the ambient temperature conditions to which the detecting resistor 12 would be subjected during a typical flight of a jet plane are represented by the unbroken line, wherein various sections between points indicate the following particular stages of the flight:

- a—b Warmup and take-off.
- b—c Cooling in level flight.
- c—d Level flight.
- d—e Combat maneuver.
- e—f Return to level flight.
- f—g Level flight.
- g—h Descent for landing.
- h—i Approach for landing.
- i—j Taxiing.
- j—k Run up to hangar.
- k—l Cooling off.

The broken horizontal line I represents the minimum temperature level at which rate of temperature rise can indicate a flaming fire, the broken horizontal line II represents the minimum temperature level at which an overheat temperature condition can be detected, and the broken horizontal line III represents the minimum temperature level at which a fixed temperature or enduring fire can be detected.

The peak A represents a rate of temperature rise condition due to a fire which the resistor 12 senses. The peak B represents a rise in temperature at a slow rate which an overheat condition would produce. The peak C represents a rise in temperature at a slow rate which a

smoldering fire would produce. These conditions and the effect thereof on the detecting network will now be described with reference to Figs. 1 to 4.

In Fig. 1, the network is shown in its normal or non-operated condition while the temperature which the resistor 12 senses is below 600° F. and the rate-of-rise due to overheat above 530° F. is not sufficiently rapid to be detected. Both of the indicators 17 and 18 are in their off position, the relays 23 and 24 are not energized and their switch means are open except that the element 30 engages the contact 31, and both of the lamps 36 and 47 are unilluminated or dark.

In the event a temperature condition occurs which is simulated by the peak A, whereby a rapid rise in temperature is sensed as in the case of a sudden burst of flame, the rise in temperature above 530° F. causes the rate-of-rise network to change the polarity sensed by the indicator 17, whereby this indicator goes to its on position, as shown in Fig. 2, and effects operation of the relay 23 and illumination of the lamp 36 under the control of this relay.

If the flame goes out quickly by itself, the temperature of the sensing resistor drops and its resistance increases to cause the indicator 17 to return to its initial position shown in Fig. 1, whereby the relay 23 is de-energized and the lamp 36 goes out. Likewise, if the rise in temperature ceases or is at a slower rate than can be sensed by the rate-of-rise network, the indicator 17 returns to its initial position (Fig. 1). However, should the temperature sensed go above 600° F. (without further rate-of-rise detection), the polarity sensed by the indicator 18 is changed whereby this indicator goes to its on position, as shown in Fig. 3, and effects operation of the relay 24 and illumination of the lamp 47 which is now connected across the conductors 10 and 11 through switch element 30, contact 31, switch element 45 and contact 46 and indicates a post-fire overheat condition. If the temperature sensed goes above 700° F. (with or without rate-of-rise detection) the indicator 17 again goes to its on position as shown in Fig. 4, to operate the relay 23 which causes the switch element 30 to disengage its contact 31 to put out the lamp 47 and causes the element 30 to engage its contact 32 to illuminate the lamp 36.

The peak B represents a slow rise in temperature created by an overheat condition above 600° F. This simply causes the network to change from the condition shown in Fig. 1 to that shown in Fig. 3 with only the lamp 47 being illuminated.

The peak C represents a slow rise in temperature created by a smoldering fire. As the temperature goes above 600° F., the lamp 47 is illuminated (Fig. 3) and, when the temperature goes above 700° F., the lamp 36 is illuminated and the lamp 47 goes out (Fig. 4).

Thus, by noting which lamps are illuminated and the sequence of illumination thereof, various temperature conditions can be discriminated to determine their cause, as illustrated by the table about to follow.

Cause

60	I. Flaming fire:
	A. Momentary 36 on—36 off.
	B. Momentary with overheat 36 on—36 off—47 on—47 off.
	C. Enduring—
65	36 on—36 off—47 on—47 off—36 on—36 off—47 on—47 off.
	II. Overheat: 47 on—47 off.
	III. Smoldering fire:
	47 on—47 off—36 on—36 off—47 on—47 off.
70	From this table, it will be observed that each time an enduring first of the flaming or smoldering type is indicated by sensing a temperature above 700° F., a post-fire overheat condition is indicated which indication in most cases will endure only momentarily because extinguishment of the fire also may rapidly cool the sensing resistor

12, whereby the increment of time while its temperature drops from 700° F. to 600° F. is insufficient to effect operation of the indicator 18 to its on position or more than momentarily cause the same to be so operated.

From the foregoing description, it will be seen that the present invention provides a simple, practical, and reliable network for discriminating the causes of various temperature conditions.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

I claim:

1. In a condition responsive system, the combination of a source of unidirectional current, first and second resistance elements connected in series across said source, parallel third and fourth resistance elements and another resistance element connected in series therewith across said source, said elements having resistance values to provide a pair of voltage dividing bridges normally unbalanced in one direction and said first resistance element being constructed and arranged so that the resistance thereof changes in response to a predetermined condition to another value whereby the bridges go towards unbalance in the opposite direction, an electromagnetically operable device connected in voltage dividing relationship across said third element and the junction of said first and second elements, and a second electromagnetically operable device connected in voltage dividing relationship across said fourth element and the junction of said first and second elements.

2. A system according to claim 1, wherein said third element has a much lower resistance value than said fourth element to expedite resetting of said first electromagnetically operable device.

3. A system according to claim 1, wherein the voltage dividing relationship of said third and fourth elements can be adjusted.

4. A system according to claim 1, including a signal circuit for each of said electromagnetically operable devices and under the control thereof.

5. A system according to claim 1, wherein each of said electromagnetically operable devices includes a pair of switch contacts, one connected to each side of said source, and a switch arm for selectively engaging said contacts connected through a diode to one side of said source; a relay having a switch contact and a switch arm is connected across the last mentioned side of said source and each of said switch arms; and a signal device is connected across the last mentioned side of said source and each of said relay switch contacts, one of said relays having a second switch contact and having its switch arm connected to the other side of said source, said second switch contact being connected to said switch arm of said other relay.

6. In a condition responsive system, the combination of a source of unidirectional current, first and second resistance elements connected in series across said source, third, fourth and fifth resistance elements connected in parallel-series across said source, said elements having resistance values to provide a pair of voltage dividing bridges in which said first, second and fifth elements are common thereto, said bridges being normally unbalanced in one direction and said first element being constructed and arranged so that the resistance thereof changes in response to a predetermined condition to another value whereby the bridges go towards unbalance in the opposite direction, an electromagnetically operable device connected in voltage dividing relationship across said third element and the junction of said first and second elements, and a second electromagnetically operable device connected in voltage dividing relationship across said fourth element and the junction of said first and second elements.

7. fourth element and the junction of said first and second elements.

7. In a system for detecting heat due to various causes, the combination of a source of unidirectional current, first and second resistance elements connected in series across said source, parallel third and fourth resistance elements and another resistance element connected in series therewith across said source, said elements having resistance values to provide a pair of voltage dividing bridges, said bridges being normally unbalanced in one direction and said first element being constructed and arranged so that the resistance decreases in response to a predetermined higher temperature condition to another value whereby the bridges go towards unbalance in the opposite direction, a time constant network including an electromagnetically operable device connected in voltage dividing relationship across said third element and the junction of said first and second elements for indicating a fire, and a second electromagnetically operable device connected in voltage dividing relationship across said fourth element and the junction of said first and second elements for indicating an overheat condition.

8. A system according to claim 7, including a signal circuit for each of said electromagnetically operable devices and under the control thereof so arranged and interrelated to discriminate between a sudden fire, an overheat condition and a slowly burning fire.

9. A system according to claim 7, wherein said elements have resistance values whereby said first device responds to a sudden fire above a given temperature level and responds to a slowly burning fire above a higher temperature level, and said second device responds to an overheat condition above an intermediate temperature level.

10. A system according to claim 9, wherein the resistance value of said third and fourth elements can be adjusted to set levels at which said devices are rendered responsive.

11. A system according to claim 10, wherein each of said electromagnetically operable devices includes a pair of switch contacts respectively connected to sides of said source and a switch arm for selectively engaging said contacts connected through a diode to one side of said source, a relay is connected across the last mentioned side of said source and each of said switch arms having a switch contact and a switch arm, and a signal device is connected across the last mentioned side of said source and each of said relay switch contacts, one of said relays having a second switch contact and having its switch arm connected to the other side of said source, said second switch contact being connected to said switch arm of said other relay.

12. In a system for detecting heat due to various causes, the combination of a source of unidirectional current, first and second resistance elements connected in series across said source, third, fourth and fifth resistance elements connected in parallel-series across said source, said elements having resistance values to provide a pair of voltage dividing bridges in which said first, second and fifth elements are common thereto, said bridges being normally unbalanced in one direction and said first element being constructed and arranged so that the resistance decreases in response to an increase in temperature to another value whereby the bridges go towards unbalance in the opposite direction, an electromagnetically operable device connected in voltage dividing relationship across said third element and the junction of said first and second elements for indicating a fire, and a second electromagnetically operable device connected in voltage dividing relationship across said fourth element and the junction of said first and second elements for indicating an overheat condition.
